[57] CLAIM

I/We claim the ornamental design for a paint can caddy, as shown.

DESCRIPTION

FIG. 1 is a top plan view of our paint can caddy showing our new design;

FIG. 2 is a front elevational view thereof;

FIG. 3 is a left side elevational view thereof;

FIG. 4 is a right side elevational view thereof;

FIG. 5 is a rear elevational view thereof;
FIG. 6 is cross sectional view shown on line 6—6 of FIG. 1;

FIG. 7 is a bottom plan view thereof; and,

FIG. 8 is a perspective view thereof.

1 Claim, 2 Drawing Sheets

FIG. 1.

FIG. 2.

FIG. 3.

FIG. 4.

FIG. 5.

FIG. 6.

FIG. 7.

FIG. 8.
